UNITED STATES PATENT OFFICE

2,053,589

ELECTRIC SOCKET

John Weritz, Cicero, Ill.

Application June 13, 1934, Serial No. 730,505

4 Claims. (Cl. 173—337)

This invention relates to electric sockets and it consists in the constructions, arrangements and combinations herein described and claimed.

It is a primary purpose of the invention to provide a socket wherein the lamp or similar device is mounted at an angle to the supporting surface, such as a molding strip or other finishing of a room.

It is also an object of the invention to provide a fixture of the above specified type in which twin sockets are embodied as a unitary and compact structure.

It is a still further object of the invention to provide a simplified construction of electric fixture embodying novel socket shell mounting means, as well as comprising simplified means for wiring the socket.

Additional objects, advantages and features of invention will be apparent from the following description and accompanying drawing, wherein

Figure 1 is a perspective view of a socket constructed in accordance with my invention.

Figure 2 is a vertical section therethrough.

Figure 3 is a rear elevation of the socket illustrating the wiring arrangement.

Figure 4 is a section on the line 4—4 of Figure 2.

Figure 5 is a section on the line 5—5 of Figure 2.

Figure 6 is a perspective view of a combined insulating contact mounting block.

Figure 7 is a side elevation of a modified form of socket.

Figure 8 is a vertical section therethrough.

Figure 9 is a top plan view thereof, and

Figure 10 illustrates a structure whereby the sockets may be spaced from the supporting surface in order to accommodate lamps of more than the average diameter.

There is illustrated in Figures 1 to 5 inclusive, a fixture generally designated by the reference character 10, which in the present instance is molded as an integral body, from any suitable insulating material, such as porcelain. The fixture includes a back member 11 and tubular open-ended shell-receiving body 12, which may be suitably reinforced intermediate its length by a rib 13. The body 12 is of slightly less length than the back portion 11, so that the end portions extend beyond the body, and respective end portions are apertured as at 13', for the purpose of receiving fastening screws, not shown.

The back 11 includes a pair of longitudinally extending channel-ways 14 defined by a pair of side walls 15 and medial wall 16, as may be clearly seen in Figures 2, 3, and 4. The walls 15 and 16 are formed as integral portions of the fixture

body 10 and preferably project therefrom, a distance sufficient to completely house electric cables or wires when positioned therewithin, as will be explained in greater detail hereinafter. The medial wall 16 is of substantial width and is provided with recesses 17 and 17' one of each, opening upon respective channels 14. An aperture 18 is formed in each recess opening upon the tubular body 12, one of the apertures being positioned in the middle vertical plane of the fixture 10, while the other aperture is positioned therebelow and in the same plane.

Within the tubular body 12 there is an insulator disk 19, having a square axial bore receiving a square contact block 20 of a length to project 15 beyond the disk 19 upon opposite sides thereof. The disk 19 has an aperture 21 formed therein adapted to align with a threaded aperture 22 formed in the contact block 20 when assembled therein.

Attention is now invited to Figure 4 of the drawing, wherein it will be seen that a contact plate 23 is seated within the recess 17, held in position therewithin by a screw 24. The screw 24 passes through an aperture formed in the plate 23, and aligned apertures 18—21 and threaded aperture 22 of the contact block 20. By the construction presented, it will be apparent that the disk 19 and contact block 20 will be effectively held in position within a medial portion 20 of the fixture 10. The block 20 is formed from suitable metal, such as brass, and inasmuch as the screw 24 will be of a similar material, these parts will therefore be electrically connected with the plate 23.

From the foregoing description, it will be apparent that the tubular body portion 12 is divided by the disk 19, defining socket portions 25, these portions having their open ends presented in opposite directions. Fixed upon opposite sides 40 of the disk 19 by screws 26 there are screw-threaded socket shells 27 and 27'. The shells 27—27' are electrically connected to complete the circuit to one side of an electromotive source, and in the present instance, the shell 27' has associated therewith a plate member 28 bifurcated to provide legs 29. The legs 28 are disposed upon opposite sides of the contact block 20 and are apertured to receive respective screws 26. 50 The shell 27' is provided with the usual inwardly extended flange 30 and the plate 28 is of a size to overlie the flange, so that with the aperture of the socket shells in alignment with apertures 26' of the disk, upon tightening of the screws 26 55

the shells 27—27' will be drawn into snug contacting relation with the disk 19.

The plate 28 comprises a right angular extension 31, bent so as to lie flush with the back wall 11, and in order to accommodate the extension as described, the shell 27' is cut away, as at 32.

A contact plate 33 seated within the recess 17' is electrically connected with the extension 31 by a screw 34, the screw passing through the rear wall 11 by way of the aperture 18 associated with the recess 17'.

From the foregoing it will be seen that the socket shells 27—27' are securely held in place 15 and that each socket is in electrical circuit with the source of supply, so that each socket is energized irrespective of the other.

The leads 35—35' are laid within respective channels 14 and the leads are bared at points 20 opposite the contact plates 23—33, and respective gripping plates 36, in bearing relation with the plates 23—33 and the bared portions of the leads 35—35' are provided, the plates 36 being secured to respective contact plates by screws 25 37. Obviously, by tightening the screws 37 the plates 36 will draw the bared wire into engagement with the plates 23—33, one lead establishing connection with the contact block 20, while the other lead completes the circuit through the 30 sockets 27—27'.

Ordinarily, I provide an insulator or spacer plate 38 between the leads 35—35' and the back 11, this plate being substantially the same size as the back 11, but is cut out intermediate its length 35 to permit insertion of the ribs 15—16 therethrough, and is also provided with apertures 39 for alignment with respective apertures 13 of the back.

The number of plates 38 may be increased, as 40 indicated in Figure 10, these plates functioning to space the fixture 10 from its supporting surface, as would be required to accommodate a lamp of more than the average diameter.

In order to effectively cover the gripper plates 36, the medial rib 16, at the ends thereof project outwardly a short distance beyond the ribs 15, defining head portions 40, and opposed faces of the head portions 40 are slotted as at 41. An insulating strip 42 is slidably retained between 50 the opposed slots, as indicated in Figures 2, 4, and 5) the strip 42 being of a size to completely cover the gripper plates, fastening screws, etc.

In Figures 7, 8 and 9, I have illustrated a modification of the fixture wherein a single socket is 55 involved, and in this instance, the fixture 50 includes a back 51, apertured as at 52 for reception of mounting screws, not shown. A cup-like member 53 is integrally formed with the back member, and upon the base 54 there is 60 seated an insulator disk 55, similar in every respect to the disk 19, previously described, with the exception that the contact block 56 stops flush with the supporting surface of the disk.

Channels 57—58 are formed in the back 51, 65 similar to the channels 17—17', and apertures 59—60 are provided, extending from respective channels 57—58 to the interior of the cup member 53. A screw 61 engaged through the aperture 59 secures a contact plate 62 within the 70 channel 57, and also passes through the aperture 63 of the disk, and in screw-threaded engagement with an aperture 64 of the contact block 56. The disk and contact block are thus securely held in position in the fixture. A screw 75 threaded shell 65 is seated upon the disk 55, the

shell having an inturned flange 66, suitably apertured at diametrically opposite sides, adapted to align with apertures 67 of the disk 55. A bifurcated plate member 68 is positioned within the shell, the legs 69 thereof overlying the flange 66. The legs 69 have threaded apertures adapted to align with apertures of the flange, and the apertures 67 of the disk 55 and through these aligned apertures a screw 70 is passed, and since the screws are in threaded engagement with the 10 legs 69 of the plate 68, the shell 65 and plate 68 will be securely held to the disk 55.

The plate 68 includes an angular extension 71, lying flush with the inside wall of the fixture, and further has a threaded aperture aligned 15 with the aperture 60, and in order to provide electrical circuit with the plate 68, a contact plate 72 within the channel 58 is fixed thereto by means of a screw 73, which passes through the aperture 20 60 of the back 51.

As in the first form of the fixture, gripper plates 74 are associated with each of the contact plates 62—72, for the purpose of securing respective leads from the source of electromotive energy,

The last described form also includes the head 25 portions 75, slotted in opposed faces as at 76 for the purpose of receiving insulator plates, not shown.

From the foregoing it will be seen that I have 30 provided an electric fixture of extreme simplicity, both as to assembly and installation, and while I have shown and described preferred constructions thereof it should be understood that I do not confine myself to the exact details of construction set forth, and consider as my own, all 35 such modifications as fairly fall within the scope of the appended claims.

I claim:

1. An electric fixture comprising a body having a socket and integrally connected back wall, an insulator disk within the socket, said disk having an opening formed medially and extending axially of the disk, a contact block mounted in the opening of the disk of a length to project beyond the ends thereof, said disk and block having aligned apertures, the aperture of the block being threaded, an aperture in the back wall of the fixture in alignment with said first two named apertures, a contact plate mounted in the back wall, said contact plate having an aperture aligned with the first mentioned apertures, a screw extended through the aligned apertures and in threaded engagement with the aperture of the contact block; a socket shell within the socket, the shell having an inturned apertured flange adapted to rest upon the disk, the disk having apertures for alignment with the apertures of the flange, a bifurcated plate member within the shell and positioned upon the flange, the bifurcated plate member having apertures aligned with the flange and the disk for reception of mounting screws, a second contact plate mounted in the back wall, apertured to receive a mounting screw, said screw extending through the back wall and in threaded engagement with the bifurcated plate, 50 and wire gripper plates associated with each of the contact plates.

2. An electric fixture comprising a body having an open-ended socket and integrally connected back wall, an insulator disk medially of the length of the socket, said disk having an opening formed medially and extending axially of the disk, socket shells mounted upon opposed faces of the disk and electrically connected together, a contact block mounted in the opening 75

of the disk and projecting beyond the faces thereof and disposed medially of the socket shells, an aperture formed in the disk, an aperture formed in the back wall in alignment therewith, a pair of contact plates mounted in the wall, a screw extended through one of said plates and aligned apertures of the wall and disk and in screw-threaded engagement with the contact block, said other contact plate being electrically connected with one of the socket shells, and wire gripper plates associated with each of said contact plates.

3. An electric fixture comprising a body having an open-ended socket and integrally connected back wall, a pair of contact plates mounted in the back wall, an insulator disk positioned medially of the length of the socket, said disk having a square opening extending axially therethrough, socket shells mounted upon opposed faces of the disk and electrically connected together, one of the sockets being electrically connected with one of the contact plates, a contact block mounted in the opening of the disk and complementary thereto and projecting upon opposite sides thereof and medially of said socket shells, a mounting screw associated with the other contact plate and extending through the back wall, and disk, and in screw-threaded engagement with the contact block, contact gripper plates associated with said contact plates, channel-ways formed in the back wall for recep-

tion of electrical leads, said wall further having head members of a height slightly greater than the channel-ways, said head members having opposed slots for slidably receiving an insulator cover plate.

4. An electric fixture comprising a one-piece open-ended body having a back wall, an insulator disk positioned medially of the length of the body, said disk having a substantially large angular opening extending axially therethrough, a substantially large angular contact block snugly mounted in the opening, said block being of a length to project beyond the ends of the disk whereby to present broad contact surfaces, said disk and block having aligned apertures, the aperture of the block being threaded, a pair of contact plates mounted in the back wall, one of said plates having an aperture aligned with an aperture in the back wall and said first two named apertures, a screw extended through aligned apertures and in threaded engagement with the block, a socket shell mounted upon each face of the disk, said shells having inwardly turned flanges, a bifurcated plate member within one of the shell members and positioned upon the flange thereof, fastening means extended through the plate, flanges and disk member for electrically connecting the shells together, said bifurcated plate having an angular extension in electrical connection with the other of said contact plates.

JOHN WERITZ.
